(57) **CLAIM**

The ornamental design for a display screen, or portion thereof, with a graphical user interface, as shown and described.

DESCRIPTION

FIG. 1 is a first front view in a sequence of a display screen, or portion thereof, with a graphical user interface showing the new design;

FIG. 2 is a second front view in the sequence thereof; and, FIG. 3 is a third front view in the sequence thereof.

The broken lines showing the display screen or portion thereof form no part of the claimed design. The remaining broken lines showing portions of the graphical user interface form no part of the claimed design.

The appearance of the transitional image sequentially transitions between the images shown in FIGS. 1-3. The process or period in which one image transitions to another image forms no part of the claimed design.
